UNITED STATES PATENT OFFICE.

PAUL REINICKE, OF KÖTHEN, GERMANY.

STRAINING-CYLINDER FOR PULP.

No. 826,193.

Specification of Letters Patent.

Patented July 17, 1906.

Application filed January 4, 1906. Serial No. 294,582.

To all whom it may concern:

Be it known that I, PAUL REINICKE, manufacturer, a subject of the Duke of Anhalt, residing at No. 19 Baasdorferstrasse, Köthen, 5 in the Duchy of Anhalt, German Empire, have invented certain new and useful Improvements in a Quickly-Rotating Straining-Cylinder for Pulp, of which the following is a specification.

10 The quickly-rotating straining-cylinders as constructed up to now consist of a cylindrical skeleton to which the sieve-plates forming the mantle are secured by means of hoops in such a manner that the sieve-plates may be 15 easily removed in order to be cleansed.

My improvement relates to straining-cylinders constructed in the aforescribed way, and in order to make my improvement more clear I refer to the accompanying drawings, 20 in which similar letters denote similar parts throughout the several views, and in which—

Figure 1 is a longitudinal section through a straining-cylinder embodying my invention, the left - hand portion of the figure being 25 shown in side view. Fig. 2 is a cross-section through the cylinder shown in Fig. 1. Fig. 3 shows, on a larger scale, a cross-section through one of the skeleton-bars with its neighboring parts. Fig. 4 is a plan of the 30 parts shown in Fig. 3; and Fig. 5 is a view similar to Fig. 4, but showing another portion of the cylinder.

The skeleton of the cylinder consists generally of the two frontal rings *b b*, which are 35 connected with each other by means of bars *c*, having a cross-like section, as shown in Fig. 3, and between the frontal rings *b* the bars *c* are connected with each other by hoops *d*, as shown in Fig. 1. The sieve-mantle consists generally of four parts arranged one parallel to the other, all the parts being retained 40 upon the skeleton before described by hoops *e*, Figs. 1 and 2. The frontal ends of each sieve-plate abut tightly against the frontal 45 rings *b*.

Straining-cylinders constructed in the before-described manner are possessed by the drawback that even under uniform conditions—such as uniform pulp, uniform rotary 50 speed, and the like—their manner of operation is not uniform, so that the effect of the straining-cylinder is comparatively low. This is, as has been ascertained, due to the fact that in order to obtain also a uniform effect 55 the sieve-plates must be placed and adjusted and fixed to the skeleton in such a manner

that the slots of the plates are located exactly at right angles to the longitudinal axis of the cylinder. Where means are afforded to let the slots assume and keep this proper 60 position, the effect of a straining-cylinder constructed in such a manner will be always absolutely uniform.

In the known straining-cylinders the sieve-plates, each of which has a length of about 65 three meters, are adjusted principally by eyesight, and only a considerably very short portion of each plate abuts against the respective frontal ring of the skeleton, so that the slots of the plates assume easily a somewhat, 70 although perhaps very slight, oblique position with respect to the longitudinal axis of the cylinder. Owing to this position, the slots act practically similar to the threads of a screw, and instead of allowing the mixture 75 consisting of the fibers and the liquor wherein the fibers are suspended to pass through the slots in the proper way the slots in consequence of their obliqueness cause a certain portion of the fibers to move to one side 80 of the cylinder, so that a correspondingly greater quantity of liquor is required and a comparatively greater consumption of power is entailed. Now to prevent these drawbacks by letting the slots assume and keep a 85 perfectly proper position—*id est*, exactly at right angles with respect to the axis of the cylinder—the longitudinal bars *c* of the skeleton are provided with lugs or other projections—for instance, ledges *r*, Fig. 4, or separate 90 projections *r'*, Fig. 5, or other means adapted to act as an abutment or as abutments for the sieve-plates *a*, so that these latter do not abut solely at their frontal ends against the frontal rings, as hitherto, but at 95 their longitudinal sides too. This is distinctly to be seen in Figs. 4 and 5. Where there are ledges, as in Fig. 4, the longitudinal sides, rims, or edges may be perfectly straight; but where there are separate projections, such as 100 *r'* in Fig. 5, the sieve-plates are provided with recesses adapted to receive the said projections. The height of the projections, lugs, ledges, or the like need only be such as corresponds to the thickness of the sieve-plates *a*; 105 but, in fact, I prefer to let the ledges or the like have a somewhat greater height, so as to obtain the further advantage that when during the rotation of the cylinder pieces of wood or other larger parts of the pulp to be purified 110 come in contact with the sieve-plates they cannot get to the rims of the latter, whereby

2
the rims might be bent and become untight. Further, where ledges or the like of a greater height are used it is preferable to provide the plates *a* with a reinforcement *v*, secured to the outer side of each sieve-plate and being so arranged that they are located below the outer hoops *e*, so as to fill up the space formed by the sieve-plate and the hoop in consequence of the greater height of the respective projections; but instead of attaching the reinforcements *v* firmly to the sieve-plates *a* there may be special small plates similar to the reinforcements adapted to be shoved between the sieve-plate and the hoop, so as also to fill up the space before mentioned.

Having now described my invention, what I desire to secure by a patent of the United States is—

1. A rotating straining-cylinder comprising two end pieces *b*, bars *c* of cross-shape in cross-section connecting the two end pieces together, segmental sieve-sections resting on

the arms of the cross-shaped bars and having their edges abutting top piece *r* thereof and hoops surrounding the sieve-sections and 25 cross-bars for holding the sections in place.

2. A rotating straining-cylinder comprising two end pieces *b*, bars *c* of cross-shape in cross-section connecting the two end pieces together, segmental sieve-sections resting on 30 the arms of the cross-shaped bars and having their edges abutting top piece *r* thereof, reinforcing-bands *v* arranged transversely on the sieve-sections and of substantially the same height as the top piece of the cross and hoops 35 surrounding the cylinder and resting on the said reinforcing-pieces.

In witness whereof I have hereunto set my hand in presence of two witnesses.

PAUL REINICKE.
